US00D901023S

(12) **United States Design Patent** (10) Patent No.: **US D901,023 S**
(45) Date of Patent: **** Nov. 3, 2020**

(54) **WEARABLE MUSCULAR STRENGTH AID APPARATUS**

(71) Applicant: **LG Electronics Inc.**, Seoul (KR)

(72) Inventors: **Kyutae Park**, Seoul (KR); **Jinju Kim**, Seoul (KR); **Seunghyun Song**, Seoul (KR); **Seongmin Kim**, Seoul (KR); **Wookjun Chung**, Seoul (KR); **Sojin Park**, Seoul (KR)

(73) Assignee: **LG ELECTRONICS INC.**, Seoul (KR)

(**) Term: **15 Years**

(21) Appl. No.: **35/507,111**

(22) Filed: **Dec. 20, 2018**

(80) **Hague Agreement Data**

Int. Filing Date: **Dec. 20, 2018**

Int. Reg. No.: **DM/202026**

Int. Reg. Date: **Dec. 20, 2018**

Int. Reg. Pub. Date: **Jul. 26, 2019**

(51) **LOC (12) Cl.** **24-01**

(52) **U.S. Cl.**

USPC **D24/190**

(57) **CLAIM**

The ornamental design for a wearable muscular strength aid apparatus, as shown and described.

DESCRIPTION

1. Wearable muscular strength aid apparatus

1.1 : Perspective

1.2 : Front

1.3 : Back

1.4 : Left

1.5 : Right

1.6 : Top

1.7 : Bottom

The broken lines depict portions of the wearable muscular strength aid apparatus that form no part of the claimed design; the fine lines on the drawings indicate the flat surface or curved surface; reproduction 1.1 is a front perspective view of the wearable muscular strength aid apparatus; reproduction 1.2 is a front view thereof; reproduction 1.3 is a back view thereof; reproduction 1.4 is a left view thereof; reproduction 1.5 is a right view thereof; reproduction 1.6 is a top view thereof; and reproduction 1.7 is a bottom view thereof; this is a design for a wearable muscular strength aid apparatus made of textile, synthetic resign and metal; the claimed design supports the hip and spine.

1 Claim, 7 Drawing Sheets
